CIGARETTE LIGHTER

John C. Lockwood, Atlanta, Ga., assignor to Scripto Inc., Atlanta, Ga.

Filed Apr. 28, 1972, Ser. No. 248,801

Term of patent 14 years

Int. Cl. D27—05

U.S. Cl. D48—27 R

FIG. 1

FIG. 2

FIG. 3

FIG. 4

FIG. 5

FIG. 1 is a front elevational view of the cigarette lighter of my design;

FIG. 2 is a left end elevational view of the lighter shown in FIG. 1;

FIG. 3 is a right end elevational view of the lighter shown in FIG. 1;

FIG. 4 is a top plan view of the lighter shown in FIG. 2; and

FIG. 5 is a bottom plan view thereof.

The rear elevational view of the lighter embodies the same configuration as shown in the front elevational view in FIG. 1.

I claim:

The ornamental design for a cigarette lighter, as shown and described.
